ATTORNEY

UNITED STATES PATENT OFFICE.

MARTIN L. BRACKEN, OF NEW YORK, N. Y.

RECORD CARD.

Application filed January 31, 1925. Serial No. 6,089.

This invention relates to improvements in record cards.

The principal object of the invention resides in the provision of a record card for receiving indicia to be arranged in alphabetical or chronological order, a number of which are adapted to be stored in a holder for reference purposes, and which are normally positioned in pack formation one next to the other whereby the indicia contained thereon is concealed, but which cards may be moved to expose a portion of the same upon the placing of the finger of the hand thereon which will facilitate a quick removal of any one particular card.

Another object of the invention relates to a record card which eliminates the soiling of the corners of the card when it is desired to remove the same from a pack thereby assuring a neat and attractive record at all times.

A further object is to provide a record card of the class mentioned which is formed from a single blank of material and functions as above mentioned without the aid of any mechanical parts other than the finger of the operator, thereby reducing the cost of manufacture to a minimum.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a plan view of the blank from which my improved record card is formed.

Figure 2 is a similar view showing the same folded for use.

Figure 3 is a perspective view of a plurality of cards disposed in normal position.

Figure 4 is a similar view showing the manner of spacing the same.

Figure 5 is an end view of the cards in position as shown in Figure 4.

Figure 6 is a view of a slightly modified form of the card.

Referring more particularly to the drawing, the reference numeral 10 designates the blank from which my improved record card is formed and which may be of any suitable material such as card-board or relatively heavy paper. The blank 10 is scored or perforated horizontally as at 11 slightly to one

side of the horizontal center to provide a front leaf or flap 12 and an integral rear leaf or flap 13. The front flap is scored horizontally as at 14 adjacent the horizontal edge thereof and is formed centrally between 60 its side edges with an outwardly extending tab 15. The horizontal edge of the flap 13 is cut-away to form a recess 16 which is directly opposite the tab 15 when the blank is placed out flat as shown in Figure 1. 65

The blank 10 is folded upon line 11 to cause the flaps 12 and 13 to lie one over the other at which time the horizontal edge of the flap 13 extends above the top edge of the flap 12, while the tab 15 is disposed adjacent 70 the recess 16. It will be understood that any indicia desired may be inscribed on the cards when placed in use, with the title or subject of the indicia upon the front of the flap 13 adjacent the horizontal edge. 75

In practice, the cards are stored in pack formation with the flaps in a substantially vertical position within a holder or cabinet, at which time the indicia of the respective cards is concealed as shown in Figure 3. It 80 is now desired to expose the indicia of certain cards to permit the removal of a particular card. This is accomplished by the operator placing his finger upon the tabs with a forward push to depress the portions 17 disposed on opposite sides of the tabs, which portions are formed by the scored line 14, whereupon the same are bent to an angle with respect to the flaps and which serve as spacers for separating the flaps of the respective cards. When the portions are held depressed, the subject matter of the cards is exposed to view, at which time the desired card may be readily removed. The operation just described is clearly shown in Figures 4 and 5 of the drawing and it will be noted that the lower or folded end of the card remains stationary as only the position of the tops of the cards is affected by the action of the portions 17. If it is desired to 90 expose a large number of cards at one time, an instrument such as a pencil or ruler may be used instead of the finger to depress the tabs. 100

In Figure 6, I have shown a modified form 105 of card which is constructed in identically the same manner as that shown in the preferred form, but which is cut vertically to form a pair of record cards 18, 18. When in pack formation these cards operate in the 110

same manner as the preferred form with the exception that the tabs 19 are disposed at one side thereof.

From the foregoing description, It will be appreciated that I have provided a record card which is formed of a single piece of material, bent, cut or folded in a manner as to space the folds or flaps to expose certain indicia contained thereon to permit the quick and ready removal of a single card from a plurality of similar cards when in pack formation.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A plurality of record cards arranged in pack formation, normally concealed indicia on said cards, and bendable means on said cards operable for spacing said cards to expose said indicia.

2. A plurality of record cards arranged in pack formation, indicia inscribed on said cards and which is normally concealed, and bendable portions formed on said cards for spacing the same to expose certain of said indicia.

3. A plurality of record cards arranged in pack formation, each card comprising a pair of folds, indicia inscribed adjacent the top edge of one fold and normally concealed by the other fold, and a bendable element on said last fold for co-action with said first mentioned fold to space said folds to expose said indicia whereby any particular card may be readily removed from the pack.

4. A record card comprising a pair of sections, and bendable means on one of said sections operable for engagement with the other section for spacing the sections.

5. A record card comprising a pair of swinging sections, a bendable portion formed on one of said sections for movement into engagement with the other section for spacing the free ends of the sections.

6. A record card comprising a pair of swinging sections, a recess formed in the free edge of one of said sections, a bendable portion formed on the other of said sections, a tab extending from said bendable portion for movement in said recess upon the depression of the tab to cause said portion to engage said first mentioned section to space the same with the major portion of said other section.

7. A record card formed of a single blank of material and bent upon itself to provide swinging folds, a notch formed in the free

edge of one section, a flap co-extensive with the other section, and a tab extending from said flap for reception in said recess.

8. A plurality of record cards arranged in pack formation, each card comprising swingingly connected sections normally disposed in relatively parallel alignment, a notch formed in the free edge of one section, a bendable fold on the other section having a manipulating tab extending therefrom, the tabs of all of said cards being in alignment whereby a plurality of tabs may be depressed simultaneously to cause said folds to move to an angular position with respect to the sections to space the same, the tabs of one card extending through the notch of that particular card and overlying the fold of the next adjacent card.

9. A plurality of cards arranged in pack formation, each card comprising a pair of hingedly connected sections normally disposed one over the other, and bendable means on one of the sections of the cards operable simultaneously for spacing the sections at the top edge thereof.

10. A plurality of cards arranged in pack formation, each card comprising a pair of sections normally disposed one over the other, and bendable means on one of the sections of the cards operable simultaneously for spacing the sections at the top edge thereof.

11. A record card formed of a single blank material and scored adjacent one edge thereof to provide a bendable flap adapted to engage the next adjacent card when a plurality of cards are arranged in intimate contact for spacing the same, and a tab extending from said flap.

12. In a record card, a pair of sections, the top edge of one section extending above the adjacent top edge of the other section, and a bendable flap carried by said last mentioned section for engagement with the first mentioned section for spacing the same adjacent the top edges.

13. In a record card, a pair of sections, the top edge of one section extending above the adjacent top edge of the other section, and a bendable flap carried by said last mentioned section for engagement with the first mentioned section for spacing the same adjacent the top edges, and a tab extending from said bendable flap for reception in a notch formed in the top edge of the adjacent section.

14. A record card formed of a single blank of material and scored to provide a bendable flap adapted to engage the next adjacent card for spacing the same when a plurality of cards are arranged in intimate contact.

In testimony whereof I have affixed my signature.

MARTIN L. BRACKEN.
